A CORPORATION OF MICHIGAN.

METHOD OF TRUING GEARS.

Application filed April 10, 1922. Serial No. 551,140.

The invention relates to the art of truing gears and more particularly to that part of it which is generally known as lapping.

The lapping of gears has heretofore been effected by running two or more gears in mesh with each other and with an abrasive material between the engaging surfaces or by similarly running a gear in mesh with a rack. Where the only movement given to the gears is that of rotation about their respective axes, the results obtained are not satisfactory. This is for the reason that the grinding is only produced where there is a slipping or sliding of one surface over another, and inasmuch as the sliding upon each other of the teeth of rotating intermeshing gears with the commonly employed involute teeth is zero at the pitch circle and progressively increases on each side of said circle with a maximum at the crown of each tooth, it is evident that the grinding produced has a tendency to change the tooth from its true involute form. With certain lapping methods a relative axial reciprocation has been imparted to the intermeshing gears, or to the gear and the rack in case a rack is employed, in addition to the relative rolling, but this is also defective and inevitably results in distortion of the true involute tooth form because the effect includes that incident to the rolling as above described.

In such a lapping or grinding operation as last referred to, the amount of grinding or abrading of a surface sliding in contact with another is dependent first, on the character of the abrasive material used; second, on the area of abrading surface that is moved over each unit area of the surface to be ground or trued; and third, the amount of pressure per unit area of contact. Accordingly, to produce uniform grinding on all portions of a surface contacting with the abrading surface there must be uniformity in abrasive material, area and pressure.

The chief object of the invention is the provision in the method of truing gear teeth or the like by the rotation or combined rotation and axial reciprocation of the gear in mesh with another gear or rack, of automatic compensation for the variable slippage at different parts of the gear tooth so that the difficulty above referred to is overcome and uniform grinding is attained.

To more clearly illustrate the nature of our improvement, the principles underlying the

same are illustrated diagrammatically in the 55 accompanying drawings, in which:

Fig. 1 is a diagrammatic view showing the intermeshing teeth of a spur gear and a lap in the form of a second spur gear and indicating by the diagonal shading the relative 60 widths of zones of surface which are traversed by the mating tooth during equal angular movements.

Fig. 2 is a view similar to Fig. 1 showing the tooth of a spur gear in mesh with the 65 teeth of a lap, the lap in this instance being in the form of a rack having straight sided teeth.

Figs. 3 and 4 are respectively a sectional elevation and a side elevation of a gear in mesh with a rack surface forming a lap therefor, the section shown by Fig. 3 being taken on the line 3—3, Fig. 4.

Fig. 5 is a view similar to Fig. 3 showing a modified construction.

In Fig. 1 is shown a portion of a spur gear 1 having teeth 2, 2 of involute form in mesh with correspondingly shaped teeth 3 of a lap 4, which in this instance is in the form of a second spur gear. The relative 80 widths of zones traversed by the mating tooth for equal angular movements of either the gear or the lap are indicated by diagonal shading on the body of each tooth. It will be observed that these zones vary in thickness 85 from the root towards the crown of each tooth. It will also be observed that when two teeth are in mesh that the smallest zones on one are adjacent the largest on the other. As, for instance, zones *a* and *b* on the gear 1 are adjacent zones *a'* and *b'* on the lap 4. As the zones indicate the amount of surface traversed by the mating tooth for equal angular movements, the zones will have to traverse each other during a unit 90 amount of such movement, which, due to the difference in width of the contacting zones, will result in a relative sliding between the contacting surfaces. It will also be observed that the intermediate zones are more nearly 100 equal. This means that the relative sliding becomes progressively less as the point of engagement approaches the mid portions of the respective teeth, with zero sliding at the pitch line. It will thus be seen that this relative sliding of the tooth surfaces is greatest at the extremities of the intermeshing teeth and gradually decreases to zero at the pitch line.

As the grinding away of the tooth surfaces occurs only where there is relative sliding it follows that during the relative rotation of a spur gear in mesh with a lap in the form of a second spur gear the contacting surfaces will be ground away more at their extremities than at the pitch line. As stated, it has been proposed to combine an axial reciprocation of either the gear or the lap simultaneously with the relative rotations, but this is also defective as the sliding which is incident to the relative rotation above noted, is still present.

In Fig. 2 we have shown a portion of a spur gear 5 with a tooth 6 of involute form in mesh with the teeth 7, 7 of a lap 8 which in this case is in the form of an involute rack having straight sided teeth. The relative widths of the zones traversed by the mating teeth for equal angular movements of the gear to be ground are indicated by diagonal shading, as in the previously described case. It will be observed however that the zones on the rack tooth are equal in width. The relative sliding between the contacting teeth will be zero at the pitch line, as in the first instance but the variance in the relative sliding between the contacting surfaces above and below the pitch line is not the same as in the previously described example; however, it can be readily ascertained by comparing the widths of the zones on the adjacent surfaces of the intermeshing teeth. It has also been proposed to combine a reciprocation of the rack parallel to the gear axis (or an axial reciprocation of the gear) simultaneously with their relative rotation; but, as in the previous case, there will still be a difference in the grinding effect due to the above noted sliding action incident to the rotating movement.

If, during the relative rotation and simultaneous reciprocation of the intermeshing gear and lap, the length of the reciprocation of the lapping surfaces could be varied in inverse proportion to the amount of sliding incident to the rolling action, the area of abrading surface moving over each unit area of the surface to be ground could be made uniform throughout. This supposed variable reciprocation is not feasible, but if, in place of a continuous surface on the lap tooth, this surface is interrupted or cut away with the width of the interruptions varying in direct proportion to the amount of relative sliding, the same compensation may be made for the unequal width of zones with uniform lengths of reciprocation.

As illustrative of some of the different ways in which the effective grinding area of the lap can be varied, we have shown in Figs. 3 and 4 a lap with its teeth modified in one way, and in Fig. 5 a corresponding lap with a distinctly different modification.

As shown in Figs. 3 and 4, 10 represents a gear wheel and 11 a lap in the form of a rack

in relation to which the gear wheel is reciprocated axially while rolling in mesh therewith. Any suitable means may be employed for providing this relative movement between the gear and lap, such as the one shown in U. S. Letters Patent No. 1,486,339, issued March 11, 1924, to W. E. Hoke. In this modification, the teeth of the rack are interrupted or cut away by the V-shaped channels 12. Obviously a lap of this form will have a grinding effect on the gear tooth to be lapped that progressively increases from the root of the gear tooth toward its crown.

In Fig. 5 the arrangement of lap 21 and gear 20 is similar to Figs. 3 and 4, the difference being that the interruptions or cut-away portions 22 of the lap in this instance are dove-tailed in shape with the width of interruption greater at the base of the rack tooth than at the crown. Obviously this construction has an opposite effect to that shown in Figs. 3 and 4.

In utilizing our invention one first predetermines the amount of relative sliding occurring between the contacting surfaces of the particular form of gear and lap teeth involved incident to their relative rotation, and then forms the lap so that the width of the interruptions or cut-away portions will in suitable proportion be greater at the point where the largest amount of sliding occurs and smaller where the lesser amount of sliding occurs. It will thus be seen that through the use of our method the contacting areas of the lapping surface are varied in suitable proportion to the amount of relative sliding between the contacting gear and lap surfaces incident to the relative rotating movement, to compensate for that variable sliding. Other things being equal, the contacting areas of the lapping surface should be varied in proportion to the amount of sliding incident to the relative rotating movement, but in practice this strict proportionality may be modified somewhat by the fact that variation of the contacting areas tends to affect the other two determining factors, namely, the pressure per unit area and the effect of the abrasive, and it is desirable to take this into account in determining the proper variation of the contacting areas, as can readily be done if on first trial the desired compensation is not fully secured. In considering the action of the modified lap, it is to be borne in mind that the abrasive action is mutual, affecting the lap as well as the gear.

The method as specifically described above is applicable in instances where it is desired to produce a uniform grinding of the gear tooth surfaces. This is desirable when the original contour of the gear tooth is substantially correct, and all that is needed is a smooth finished surface. However, our invention is also applicable to instances where the original tooth surface has not been cor-

rectly formed, as for instance where there is too much material at the crown portion of the gear tooth. In such an instance the interruptions or cut-away portions of the lap tooth would be so formed as to compensate for the relative sliding referred to above and at the same time so formed as to grind away more surface at the point where the excess material occurs. In order to produce this combined action of compensating for the relative sliding and the differential grinding the width of interruptions at the base of the lap tooth would be relatively smaller so as to present a larger area of abrading surface to contact with the crown of the tooth and thus correct the original defect in the tooth form, while at the same time, the lapping produces the smoothly finished surface desired. Thus by properly forming the interruptions in the lap any desired grinding effect may be produced, such for instance, as uniform grinding where the tooth form is originally correct or differential grinding where the original tooth form needs modification.

While we have described our method as applied to the grinding of gears, it is obvious that it is equally applicable to the grinding of other interrupted circular bodies; also, that it is equally applicable to the grinding of internal and external surfaces.

What we claim is:

1. In a method of grinding gears by imparting simultaneously relative rotation and axial reciprocation to a gear and a lap having complementary intermeshing teeth, the provision and use of a lap so formed that its abrasive area which is brought into contact with the gear teeth by said reciprocation varies during the relative movement of the gear and lap in suitable proportion to the amount of relative sliding between the contacting gear and lap surfaces incident to the relative rotation of the gear and lap to compensate for said sliding.
2. In a method of grinding gears by im-

parting simultaneously relative rotation and axial reciprocation to a gear and a lap having complementary intermeshing teeth, the provision and use of a lap so formed that its abrasive area which is brought into contact with the gear teeth by said reciprocation varies during the relative movement of the gear and lap in suitable proportion to the amount of relative sliding between the contacting gear and lap surfaces incident to the relative rotation of the gear and lap and to the amount of excess material to be removed to compensate for said sliding and for the said excess material.

3. The method of finishing surfaces of gear teeth to predetermined contours which consists in imparting simultaneously relative rotation and axial reciprocation to the gear and a lap having tooth-like lapping surfaces which are in abrasive contact with the gear and formed to have their surface areas which are brought into abrasive engagement with the gear teeth by the said reciprocation varied by the combined rotation and reciprocation in suitable proportion to the amount of relative sliding between the contacting gear and lap surfaces incident to the said rotation to compensate for said sliding.

4. The method of grinding toothed bodies such as gears which consists in engaging the teeth of the body with a toothed abrading tool, causing between the body and tool a relative angular motion in the plane of the gear body and also a relative transverse motion in an axial plane of the gear body and by the combined angular and transverse motion varying the area of abrasive contact of the radial faces of the tool with the teeth of the gear incident to said transverse motion in a predetermined proportion to the slip or relative sliding between the teeth of the body and the tool due to the said angular motion.

In testimony whereof we affix our signatures.
